(57) **CLAIM**

The ornamental design for a corner support for a skimmer box lid frame, as shown and described.

DESCRIPTION

FIG. 1 is a top of corner support for a skimmer box lid frame;

FIG. 2 is a bottom view thereof;

FIG. 3 is a front view thereof;

FIG. 4 is a back view thereof;

FIG. 5 is a left side view thereof;

FIG. 6 is a right side view thereof;

FIG. 7 is a top perspective view thereof; and,

FIG. 8 is a bottom perspective view thereof.

The portions shown in dashed lines are for environmental

purposes and constitute no part of the claimed design.
